UNITED STATES PATENT OFFICE.

CHARLES J. SCHULTE AND CHARLES F. WEHMEYER, OF ST. LOUIS, MISSOURI.

FOLDING OR COLLAPSIBLE CHAIR.

SPECIFICATION forming part of Letters Patent No. 561,136, dated June 2, 1896.

Application filed February 27, 1896. Serial No. 580,965. (No model.)

To all whom it may concern:

Be it known that we, CHARLES J. SCHULTE and CHARLES F. WEHMEYER, citizens of the United States, residing at St. Louis, in the 5 State of Missouri, have invented certain new and useful Improvements in Folding or Collapsible Chairs, of which the following is a full, clear, and exact description, reference being had to the accompanying drawings, 10 forming a part hereof.

Our invention has relation to improvements in folding chairs; and it consists in the novel arrangement and combination of parts, more fully set forth in the specification, and pointed 15 out in the claims.

In the drawings, Figure 1 is a side elevation of the chair folded. Fig. 2 is a side elevation of the chair unfolded into the form of a vehicle. Fig. 3 is a sectional detail on the line 20 xx of Fig. 2, and Fig. 4 is a section on line yy of Fig. 2.

The object of our invention is to construct a child's chair which under ordinary circumstances will serve the purposes of a high chair, 25 and which under other circumstances can be folded or converted into a wheeled chair or vehicle by the simple manipulation of certain parts, the details of which will be more fully hereinafter described.

30 A further object is to construct such a chair with a minimum number of parts and to simplify the device to a degree, whereby a cheap and simple apparatus results:

In detail the chair may be described as follows:

Referring to the drawings, 1 represents the 35 seat of the chair, which is provided with the rigid legs 2 3, the front pair 2 serving to retain the usual foot-rest 4'. Pivoted to the free 40 end of each of the legs 2 3 are the extension-legs 4 5, the latter having mounted thereon the wheels 6 7, the former of the wheels being located at a point above the foot-rest 4' and the latter being mounted near the lower 45 end of said leg. When the device is used as a high chair, the upper ends of the extension-legs 5 abut against the front transverse strip 8, secured to the under surface of the seat adjacent to and parallel to the front edge thereof. 50 The upper ends of the extension-legs are connected by the links 9, secured, respectively, along the outer and inner surfaces of the re-

spective legs 4 and 5, and the lower ends of the said extension-legs are similarly connected by the links 10 at a point above the 55 wheels 7, the object of connecting the links on opposite faces of the legs being to allow the latter to freely fold about the links when the chair is unfolded, as best seen in Fig. 2. Pivotedly connecting the side bars 11 of the 60 back with the lower extremities of the extensions 4 are the brace-bars 12 and the curved handle-bars 13, the medial portions of the latter and the lower extremities of the legs 4 embracing the free ends of the reduced extensions 14 of the rounds 15, which respectively connect the handle-bar and leg on one side of the chair with its corresponding handle-bar and leg on the opposite side, the extensions 14 each passing through the braces 12 70 to effect such connection.

When the device is normally used as a high chair, the parts are folded as seen in Fig. 1, in which case the shoulders 16, formed in the handle-bars adjacent to the pivotal ends of 75 the braces 12, are firmly locked under and against the lower surface of the seat 1, and the free ends of the handle-bars are additionally secured to one of the legs 4 by a swinging latch 17. When thus locked, the chair 80 cannot be accidentally collapsed by the child using it. The free ends of the handle-bars are connected by a rod 18, whose end is shown by the dotted lines in Figs. 1 and 2. When the parts are unfolded, as in Fig. 2, the members 13 serve as the handle-bars for the carriage or vehicle thus resulting.

Having described our invention, what we claim is—

1. In a folding chair, a suitable seat, rigid legs depending from the same, extensions pivoted to said legs, wheels carried by the front pair of said extensions, an abutting strip carried by the seat against which the extensions may rest when the chair is in its normally- 90 raised position, suitable links connecting the front and rear extensions, the opposite ends of each link being pivotally secured along opposite sides or surfaces of the front and rear extensions respectively, a back for said 95 chair, folding connections between said back and one pair of the extensions, and means forming part of said connections for locking the parts against the seat when the chair is 100

in its normally-raised position, substantially as set forth.

2. In a folding chair, a suitable seat, rigid legs depending from the same, extensions pivoted to said legs, wheels carried by the front pair of said extensions, an abutting strip carried by the seat parallel to the front edge thereof against which the free ends of the extensions may rest or be held when the chair is in its normally-raised position, suitable links connecting the front and rear extension-legs, one end of each link being secured pivotally along the outer surface of the rear extensions and along the inner surface of the front pair of extensions, a suitable back for said chair, suitable handle-bars pivoted to the back, rounds having reduced extensions connecting the handle-bars at approximately their medial portions, suitable braces pivotally connected to the reduced extensions of the rounds, suitable rounds connecting the bases of the rear pair of extension-legs, said latter rounds having reduced extensions connected pivotally to the opposite ends of the braces, shoulders formed with the handle-

bars in such position that when the device is folded to raise the chair the said shoulders will be in engagement with the under surface of the seat, and a suitable latch adapted to further secure the free ends of the handle-bars to the rear extension-legs, the parts all operating as and for the purpose set forth. 30

3. In a folding chair, a suitable seat, a back for the same, suitable depending legs, extensions for said legs, suitable handle-bars pivoted to the back, suitable braces pivotally connecting the handle-bars and rear extensions, and shoulders formed with the handle-bars in such position that when the device is folded to raise the chair, said shoulders will 35 be in engagement with the under surface of the seat, substantially as set forth. 40

In testimony whereof we affix our signatures in presence of two witnesses.

CHARLES J. SCHULTE.
CHARLES F. WEHMEYER.
